James D. Givens, Atty.

UNITED STATES PATENT OFFICE

2,646,706

TOOL FOR STRAIGHTENING SHEET METAL
SUCH AS IN VEHICLE BODIES AND THE
LIKE

William J. Palmer, Portland, Oreg.

Application May 22, 1950, Serial No. 163,447

1 Claim. (Cl. 81—15)

1

This invention relates to improvements in tools and attachments therefor for straightening or bending damaged sheet metal such as in vehicle bodies and the like.

It is one of the principal objects of the invention to provide a tool of this character which is of simple and rugged construction and positive and accurate in its operation of straightening dented or accidentally bent sheet metal by pressure applied to both sides of the metal over a wide area to smoothly press the metal back into its original shape in contrast to conventional methods wherein a hammer or mallet is used to pound the metal against an anvil or the like.

Another object of the invention is the provision of various shapes and sizes of pressing and forming elements or dies which are readily adapted for quick and convenient attachment to or detachment from the tool.

These and other objects will appear as my invention is more fully hereinafter described in the following specification, illustrated in the accompanying drawing and finally pointed out in the appended claim.

In the drawing:

Figure 1 is a side elevation of a tool made in accordance with my invention.

Figure 2 is a slightly enlarged sectional detail plan view taken approximately along the line 2—2 of Figure 1.

Figure 3 is a view similar to Figure 2 taken along the line 3—3 of Figure 1.

Figure 4 is an enlarged sectional detail view taken along the line 4—4 of Figure 1.

Figure 5 is an enlarged fragmentary sectional detail view showing the tool in operative engagement with a piece of metal being dealt with.

Referring now more particularly to the drawing:

In Figure 1 reference numeral 1 indicates generally the main body of the tool shaped as shown and made of material of T-section as best illustrated in Figure 4 having a horizontal portion 2 and a stiffening rib portion 3. The body member is substantially C-shaped as shown with its upper leg terminating in a housing 4 within which is rotatably mounted a pinion gear 5 by means of a reduced end portion 6 journaled within the housing as at 7. The opposite end of the pinion gear is enlarged into a shaft 8 through which an actuating handle or rod 9 extends. Slidably mounted for vertical movement through the housing 4 is a gear rack 10 whose gear teeth 11 operatively engage with the teeth of the pinion gear 5 so that rotation of the pinion gear will

2

raise or lower the rack 10 with respect to the housing 4. The bottom end of the rack 10 is reduced in diameter and threaded as at 12 for removable attachment to one of several pressing and forming elements or dies as indicated at 13 and each of which is formed with a center boss 14 internally apertured and threaded for attachment to the reduced and threaded end 12 of the rack 10.

10 The free end of the opposite leg 15 of the body member is provided with an externally threaded vertical stud 16 upon which is removably secured a companion die 17 by means of an internally threaded hub 18 which is bored inwardly from its opposite end as at 19 to receive a projection 20 formed on the under side of the die 17.

As best illustrated in Figure 5 the tool is presented to the sheet metal being dealt with by placing the concave die 13 against one side or surface of the metal being dealt with and the companion die 17 against the opposite side thereof to resist the action of the die 13 against the metal which bears against the convex surface of the die 13. The under side of the flange portion 21 of the die 13 is provided with a disc 22 of resilient material attached by means of projections 23 to said flanged portion. This flange yields or compresses at its inner periphery sufficiently to allow the metal 24 being dealt with to bend smoothly in the widest possible arc around the peripheral edges of the cavity formed in the die 13.

30 As previously pointed out, the concavity of the attachment 13 and the corresponding curvature of the companion die 17 should be greater than the area of the damaged portion of the metal to be repaired so that the entire damaged area of the metal may be positioned within the concavity of the die 13 and in a position to be backed by the anvil or companion die 17 which by reason of its firm mounting on the leg 15 of the C-shaped body member 1 will resist the downward movement of the gear rack 10 so as to force and spring the metal up into the cavity 13 beyond its normal level, then release or the backing away of the anvil or companion die 17 from the concavity of the attachment 13 will allow the metal to spring back into its normal position in relation to the undamaged portion of the metal surrounding it.

40 While I have shown a particular form of embodiment of my invention, I am aware that many minor changes therein will readily suggest themselves to others skilled in the art without departing from the spirit and scope of the invention.

Having thus described my invention, what I claim as new and desire to protect by Letters Patent is:

A metal bending and straightening tool comprising in combination a body member of substantially C formation having two opposing legs, a vertical bearing formed in the terminal end of one of said legs, a vertically disposed hub fixedly secured to the terminal end of the other of said legs, a die removably secured to said hub, said die being of circular and convex formation over its entire top surface, a gear rack slidably mounted in said vertical bearing and operable by a pinion gear rotatably mounted in the terminal end of said first-mentioned leg, a circular disc of greater diameter than said die secured to the bottom end of said gear rack, a concentric concavity formed in said disc in opposing relation to said convex surface of said die, said concavity being of mating formation to the top sur-

face of said die and equal in diameter to the diameter of said die thus leaving a relatively wide annular flat flange surrounding said concavity, and an annular plate of resilient material attached to the underside of said annular flange covering the entire surface thereof.

WILLIAM J. PALMER.
